UNITED STATES PATENT OFFICE.

HENRY O. SCHMIDT, OF NEW YORK, N. Y., ASSIGNOR TO SIMONS, BROTHERS & CO., OF PHILADELPHIA, PENNSYLVANIA.

DESIGN FOR A CANE OR UMBRELLA HANDLE.

SPECIFICATION forming part of Design No. 20,559, dated March 3, 1891.

Application filed February 6, 1891. Serial No. 380,518. Term of patent 3½ years.

To all whom it may concern:

Be it known that I, HENRY O. SCHMIDT, a citizen of the United States, residing in New York, in the county and State of New York, 5 have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

A is the body part, and terminates at the top in a ring B, formed with a small protuberance to one side near the bottom, as at C. The inner portion of the ring B is ornamented by longitudinal ribs. The body part 15 A is formed with an annular band D of highly-ornamented work, and immediately

above and below said band are ornamental 20 portions corresponding to the ribs in the portion B. The bottom of the body part is finished by an annular band E, the upper portion of which is highly ornamented, as shown.

The handle may be formed of any suitable 25 material.

Having now described my invention, what I claim as new, and desire to secure by Letters Patent, is—

The design for cane or umbrella handles, 30 substantially as herein described and shown.

In testimony of which invention I have hereunto set my hand.

HENRY O. SCHMIDT.
